(57) **CLAIM**

The ornamental design for a hand saw, as shown and described.

DESCRIPTION

FIG. 1 is a perspective view of a hand saw showing my new design;

FIG. 2 is a right side view thereof;

FIG. 3 is a left side view thereof;

FIG. 4 is a front end view thereof;

FIG. 5 is a rear end view thereof;

FIG. 6 is a top plan view thereof; and,

FIG. 7 is a bottom plan view thereof.

The broken lines in the drawings are for the purpose of illustrating unclaimed portions of the hand saw and form no part of the claimed design.
